ENGRAVING MACHINE

Frank Ackerman, Bronx, and Herman Gould,
Brooklyn, N. Y.

Application December 28, 1938, Serial No. 248,032

6 Claims. (Cl. 90—13.1)

Our present invention relates to an engraving machine and aims to provide certain improvements therein. More particularly it relates to an engraving machine which operates on the principle of the pantograph.

The primary object of our invention is to provide a relatively portable machine of the type specified adapted for reproducing by engraving ordinary characters from type or stencils or facsimile signatures onto flat, curved, or round objects, such as pencils, fountain pens, tooth brushes, pipe stems, compacts, vanity cases and the like, formed of wood, hard rubber, plastics, enamel ware and certain metals. A further object is to provide such machine wherein the pressure of the engraving cutter upon the work is maintained substantially uniform so that the depth of the engraving cut is substantially uniform regardless of the character or form of the object being engraved. A further object is to provide such machine which will be simple in construction and which can be efficiently operated by unskilled labor after a few minutes instruction.

The foregoing and other objects not specifically enumerated are accomplished by our present invention, the construction and operation of which will be understood from the detailed description which follows when considered in connection with the accompanying drawing, wherein:

30 Figure 1 is a perspective view of an engraving machine embodying our invention.

Fig. 2 is a top plan view of the operative mechanism of the machine.

Fig. 3 is a section taken substantially along the plane of the line 3—3 of Fig. 2.

Fig. 4 is a front elevation of the work support.

Fig. 5 is a fractional longitudinal section through the nose of the cutter, which latter is shown in elevation.

40 Fig. 6 is a longitudinal section through a modified form of one of the work clamping elements.

Fig. 7 is an end elevation of the work clamping element shown in Fig. 6.

Referring to the drawing, the engraving machine may be said to consist of a supporting base 10 upon which is mounted a work support 11, a cutter 12, a pantograph 13, a platen 14 and an electric motor 15.

The base 10 may be formed as a metal casting having at one corner thereof an upstanding arm or standard 16 at the top of which is an inwardly directed lug 17 which is centrally drilled to provide a pivot mounting for both the pantograph 13 and a base support 18 for the electric motor.

45 Also extending upwardly from the top of the base

10 is a pair of short pedestals 19 upon which the platen 14 is mounted.

The work support 11 consists of an angular bracket or fixed member 20 rigidly mounted on the base 10, the upright arm 21 of the bracket being formed on one face with a dove-tail slide-way 22 within which is slidably mounted one member 23 of a holding clamp, the cooperating member 24 of said holding clamp being mounted for sliding movement in a dove-tail slideway 25 in one face of the member 23. The upright arm 21 of the bracket 20 is also formed with an opening 26 therethrough through which extends pins 27 and 28 mounted on the member 23. A pin 29 also extends outwardly from the upright arm 21 and connecting said pin 29 with the pin 27 is a tension spring 30 which normally biases the holding clamp towards its uppermost position with respect to the upright arm 21 of the bracket. For moving the holding clamp downwardly 30 against the tension of the spring 30 there is mounted in a bearing lug 31 on the bracket 20 a rock-lever 32 one end of which is bent as indicated at 33 and pivotally connected to the pin 28. The opposite end of the rock-lever 32 is also 25 bent at an angle and flattened as indicated at 34 for a purpose which will presently appear. The holding clamp member 23 at its top is formed with a pair of spaced horizontally directed arms 35 which on their under faces are formed with 30 aligned inverted V-shaped grooves 36. The cooperating holding clamp member 24 is also formed with an outwardly directed arm 37, the top face of which is formed with a V-shaped groove 38 in alignment with the V-shaped 35 grooves 36. Normally the arms on the elements 23 and 24 are urged toward each other so as to clamp and hold therebetween an article which is to be engraved. To provide for this clamping engagement the element 24 is biased by a strong coil 40 spring 39 mounted within a socket formed in the member 24 and bearing at its opposite end upon a supporting plate 40 carried by the holding clamp member 23. For disengaging an article from the action of the clamping elements there 45 is provided a thumb engaging button 41 carried by a pin which is mounted in the member 24 so that upon pressing downwardly upon the button 41 the work holding clamp as a whole will first move and then the member 24 will be moved 50 relatively to the member 23 to separate the arms 35 and 37.

The pantograph 13 consists of the arms or limbs 42, 43, 44 and 45 pivoted together at the points 46, 47, 48 and the axis 49 through the 55

cutter mounting. All four of the pivot mountings are movable, the only pivot mounting of the pantograph which is fixed being that extending through the lug 47. The arm 45 is considerably longer than the other arms, to provide for reduction in size of the reproduced matter, and adjacent its free end carries a tracing stylus 50 having a hand engaging knob 51.

The cutter mounting 12 consists of a frame provided by the arm 44 which has an upwardly and reversely directed or overhanging portion 52 as best shown in Figs. 1 and 3. The arm 44 and overhanging portion 52 are each coaxially drilled along the axis 49 and each provided with a bushing extending through said drilled openings, the ends of the bushings extending beyond either face of the arms. The bushing which extends through the arm 52 is externally threaded at each end to accommodate the thumb nuts 53 and 54 while the bushing which extends through the arm 44 has a smooth surface at its upper end over which the arm 43 pivotally engages and said bushing is externally screw threaded at its lower projecting portion over which the hollow nose 55 of the cutter engages. Mounted through the bushings in the members 44 and 52 so as to be freely rotatable therein is a sleeve 56 upon which is fixedly mounted a pulley 57 between the thumb nut 54 and the end of the lever 43. Trained over said pulley is an elastic belt 58 of any approved design which engages over the pulley on the driving shaft of the motor 15. The sleeve 56 adjacent its upper end is internally screw threaded and adjacent its lower end its bore is of reduced diameter, and extending through said sleeve is a cutter element 59 which screw threadedly engages the upper end of the sleeve and snugly extends through the reduced bore at the lower end of the sleeve so as to be truly centered by said sleeve. The lower end of the cutter is ground to a very sharp point after which a cutting surface is provided by grinding away a portion of the face of the cutter at the point thereof. The cutter extends a very slight distance through the tip or apex of the cutter nose as best shown in Fig. 5 and to provide for discharge of the cutting chips, the nose is cut away as best shown in Fig. 5.

The platen 14 may be of any desired form and as herein shown is a flat plate having an undercut groove extending longitudinally thereof for receiving type, stencils or a sheet of paper 60 containing a signature facsimile which is to be reproduced by engraving. Where a paper having a name facsimile thereon is employed it may be held fixedly in place within the groove by spring clips 61 carried by slide elements 62 which may be clamped to the platen by thumb screws 63. At one end of the platen overlying the rock-lever 32 is a plunger 64 normally held in its uppermost position by a spring 65, which plunger upon being depressed will engage the flattened end 34 of the rock-lever to turn the same and in so doing move the work holding clamp downwardly against the tension of the spring 30. The platen at its opposite end is provided with a hole into which the stylus 50 may seat when not in use.

For operating the motor a switch 66 may be disposed at the front of the base of the machine or at any other suitable position thereon. The machine as a whole may be mounted upon a wooden or other supporting plate 67 so as to provide a closure for the underside of the base 75 and lend greater portability to the machine.

Operation.—The point of the cutter is first adjusted to protrude the proper distance beyond the end of the nose by adjustment of the cutter with respect to its carrying sleeve and the lock nut 59 carried by the cutter. The article to be engraved, for example a fountain pen barrel, is positioned in the V-shaped grooves and clamped between the arms 35 and 37, the spring 38 serving to firmly hold the article in place while the spring 30 functions to urge the work holding 10 clamp as a unit toward its uppermost position in which it will be engaged by the point of the cutter. A stencil or name facsimile which is to be reproduced by engraving is then positioned and held in the guide groove of the platen. The plunger 15 64 is depressed so as to move the work out of the path of the cutter. The motor is thereupon started by throwing the switch 66 and the engraving operation is commenced by bringing the tracing stylus 50 to the beginning of the facsimile 20 or other matter to be reproduced. The plunger 64 is now released thereby bringing the work into engagement with the cutter point and as the stylus 50 traces the stencil or name facsimile the cutter will reproduce the same on the article. 25 Where a space is to be provided in the engraved matter or whenever it becomes necessary to move the work out of engagement with the cutter it is merely necessary to press down upon the plunger 64 and hold it down until the stylus is brought 30 into position for continuing the engraving operation. When the subject matter to be reproduced has been completely traced the stylus is brought back and set into the opening in the platen, the motor is stopped and the work is removed from 35 the work holding clamp by pressing downwardly upon the button 41. After cleaning the engraved surface with a stiff brush the engraved matter may be filled in with a suitable wax of contrasting color to the article and permitted to dry after 40 which the excess is wiped off leaving the engraved reproduction desired in outstanding relief.

Where the article to be engraved has a varying diameter or is tapered at one end as is the case with many forms of pen barrels, such articles 45 can be suitably clamped by mounting in the V-shaped groove 38 a supplemental V-shaped element 70 in such manner as to permit of a slight rocking action of said element longitudinally of the groove. This may be accomplished 50 by forming in the element 37 a socket 71 extending normally outwardly from the dihedral angle of the groove and providing the member 70 with a pin 72 extending normally outwardly from the dihedral angle, said pin being of a size to fit into 55 the socket 71 and of a length slightly greater than the depth of said socket, as best shown in Figs. 6 and 7. The supplemental V-shaped element will permit slight tilting movement of the article within the work holding clamp as the 60 article is brought into engagement with the cutter while still serving to clamp the article during the engraving operation.

It will be noted that in view of the pivotal 65 mounting of the motor support at the fixed pivot of the pantograph that the movable pivot or axis 49 will vary in distance from the motor or in other words, the distance between the centers of the pulleys 57 and 15 will vary. Hence to take 70 up these variations while at the same time maintain an effective drive of the pulley 57 by the motor, the belt 58 is made elastic. This elasticity may be imparted to the belt either by making the belt out of a closely coiled spring wire or by 75

using a section of such coil spring between the ends of a leather or other suitable belt.

While we have herein shown a preferred and practical embodiment of our invention, it is to be understood that changes in the specific detail of construction may be resorted to within the range of engineering skill without departing from the invention.

What we claim is:

- 10 1. In an engraving machine, a pantograph, a motor driven cutter carried by one of the pantograph arms, a platen for holding the design or stencil to be traced by the stylus of the pantograph, and a work support comprising a fixed member, a work holding clamp mounted on the fixed member to move vertically relatively thereto, resilient means biasing the work holding clamp toward its uppermost position, a lever for moving the work holding clamp against the tension of the resilient means and means carried by the platen for operating said lever.
- 15 2. An engraving machine according to claim 1 wherein the lever is rockably mounted and one end of the lever is pivotally connected to the work holding clamp and the other end extends below the platen and a plunger extending through the platen adapted to rock the lever.
- 20 3. In an engraving machine, a pantograph having a stationary pivot point, a rotatable cutter carried by one of the pantograph arms, a motor support mounted to pivot about the stationary pivot point of the pantograph and a direct elastic belt drive between the motor and the cutter to insure proper driving engagement for the cutter as the effective driving distance between the motor and the cutter is varied in operation with the pantograph.
- 25 4. In an engraving machine, a rotatable cutter, a work holding clamp comprising cooperating clamping elements having V-shaped grooves

therein facing each other, resilient means biasing said elements into work clamping relation and a supplemental V-shaped element disposed in one of the V-shaped grooves of the clamping elements and adapted for limited longitudinal rocking movement therein.

5. In an engraving machine, a rotatable cutter, a work holding clamp comprising cooperating clamping elements having V-shaped grooves therein facing each other, resilient means biasing said elements into work clamping relation, one of said V-shaped elements having a socket extending normally outwardly from the dihedral angle, and a supplemental V-shaped element having a pin extending normally outwardly from the dihedral angle and of a length slightly greater than the depth of the socket with said pin seating in said socket whereby to provide for limited rocking movement of the supplemental V-shaped element.

6. In an engraving machine, a pantograph, a motor driven cutter carried by one of the pantograph arms, and a work support comprising a fixed member, a work holding clamp mounted on the fixed member to move vertically relatively thereto, said work holding clamp comprising cooperating clamping elements, one of which is carried by and movable relatively to the other, resilient means biasing said clamping elements into work clamping relation, other resilient means biasing the work holding clamp toward its uppermost position, and manually operable means for moving the clamping elements of the holding clamp away from each other against the tension of the resilient means directly acting thereon, after the work holding clamp as a unit has been moved to its extreme downward position.
